United States Patent Office

Des. 191,124
Patented Aug. 15, 1961

191,124

COVERED FOOD SERVING VESSEL

John E. Barron, Glenview, and Floyd A. Blashfield,
Evanston, Ill., assignors to Mealpack Corporation,
Evanston, Ill., a corporation of Illinois

Filed Jan. 3, 1961, Ser. No. 63,432

Term of patent 14 years

(Cl. D44—15)

FIG. 1 is an exploded perspective view of a covered food serving vessel, showing our new design;

FIG. 2 is a side elevational view; and

FIG. 3 is a top plan view.

We claim:

The ornamental design for a covered food serving vessel, as shown.
